DESIGN FOR AN AUTOMOBILE GRILLE GUARD

Frank J. Faulhaber, New York, N. Y.

Application August 23, 1947, Serial No. 141,020

Term of patent 3½ years

(Cl. D14—6)

To all whom it may concern:

Be it known that I, Frank J. Faulhaber, a citizen of the United States, residing at New York, in the county of New York and State of New York, have invented a new, original, and ornamental Design for an Automobile Grille Guard, of which the following is a specification, reference being had to the accompanying drawing, forming part thereof.

Fig. 1 is a front view of an automobile grille guard, showing my new design;

Fig. 2 is a plan view thereof; and

Fig. 3 is an end view.

The characteristic features of my design reside in the portions shown by means of full lines in the drawing.

I claim:

The ornamental design for an automobile grille guard, as shown and described.

FRANK J. FAULHABER.
